CATALYTIC DEHYDROGENATION

Miller Wade Conn, Bartlesville, Okla., assignor to
 Phillips Petroleum Company, a corporation of
 Delaware

Application August 10, 1942, Serial No. 454,311

1 Claim. (Cl. 196—9)

This invention relates to a process for preparing an improved high octane motor fuel or gasoline from any straight-run naphtha or gasoline stock, especially the normally liquid hydrocarbon condensate known as "distillate" and obtained by known methods of recovery from the hydrocarbon mixture naturally occurring in gas phase in so-called distillate wells under very high pressures exceeding 1000 pounds per square inch. As is well known, this condensate or "distillate" may be recovered from the well gas which is at a high pressure within the retrograde condensation range by lowering the pressure thereon and preferably by simultaneously scrubbing or contacting with an absorbent liquid. Methods of recovery of the condensate will be found for example in Vaughan 2,133,774; Bays 2,135,319; Vaughan 2,151,248; Bays 2,156,234; Walker et al. 2,174,336; Vaughan 2,198,098; Bays 2,212,143; Roberts 2,213,996; Buckley 2,242,173; Farris 2,245,028; Walker 2,262,744; Bays 2,272,503; Walker 2,278,750.

This "distillate" is normally liquid and may be approximately water-white in color, or in some instances more or less colored, and may or may not have been subjected to stabilization to remove the light end or "wildness" (C₄ and lighter) so that the remainder will not readily evaporate. Broadly speaking the "distillate" liquid has many of the properties of a medium to poor quality third-grade motor gasoline. It is practically water-white, sweet, non-corrosive, low in sulphur and gum, and susceptible to tetraethyl lead for raising the octane number. Practically all of it shows 10 to 20% boiling above 400° F. That is, 80-90% of it is in the gasoline boiling range. Usually it has an initial boiling point in the neighborhood of 90 to 100° F. and is fairly well distributed over the gasoline boiling range. A summary of typical characteristics is given in the following tables:

TABLE A

Summary of typical "distillate" characteristics

Gravity, °A. P. I.	54° to 70°, average around 60°
Reid vapor pressure at 100° F.	5 to 12 lbs. per sq. in.
Octane number	40 to 60
Color	30+ (occasionally straw)
Doctor test	Negative
Gum	3 to 16 Mg/100 cc.
Corrosion	Negative
Sulphur, percent by weight	0.004 to 0.022

TABLE B

Distillation characteristics (A. S. T. M.)

I. B. P.	°F	78-162
10%	°F	128-232
5%	°F	202-364
E. P.	°F	360-572
80%	°F	255-462
Per cent over 400° F. B. P.	per cent	0-38

10 This "distillate" is produced in large quantities on the Louisiana and Texas Gulf Coast, for example, at Corpus Christi, Texas.

15 It is a serious disadvantage of the condensate just described that its octane number is extremely low so that if it is attempted to use it as or in motor fuel it is necessary to add tetraethyl lead thereto in substantial amounts in order to raise its octane number to satisfactory levels. Other disadvantages are encountered in the use of the "distillate" as motor fuel.

20 The "distillate" per se, of course, is not suitable for use as motor fuel, and furthermore fractionation to give "end-point" motor fuels results in poor yields of an inferior type fuel.

25 Other types of material known as straight-run naphtha or gasoline stock are subject to the same disadvantages as the condensate just described, and my invention in its broader sense is applicable thereto. An example is straight-run gasoline made by the straight-run distillation of crude petroleum oil. Preferably the starting material has been freed from butane and lighter hydrocarbons. It may contain substantial proportions of material higher boiling than

30 gasoline, such as kerosene, gas oil, and other components boiling up to 600° or 650° F. I may treat either the entire "distillate" or naphtha or only that portion thereof which boils in the gasoline range.

35 The principal object of the present invention is to provide a process for improving the motor fuel characteristics of the straight-run naphtha or gasoline stock and especially the condensate or "distillate" of the type described above. Another object is to manufacture an improved motor fuel of high octane rating from the condensate and thereby markedly reduce the quantity of tetraethyl lead that must be added. Numerous other objects of the present invention will more fully hereinafter appear.

40 The accompanying drawing portrays diagrammatically one arrangement of equipment that has been found very satisfactory for carrying out the process of the present invention.

In accordance with my invention, the stabilized raw material, such as the raw "distillate" described above or the gasoline fraction thereof, is first subjected to fractionation in any known manner, as for example by so-called "superfractionation," in any suitable equipment which may involve a plurality of fractionating columns, to separate the high octane components thereof. These are separated at this point because they are already of sufficiently high octane number and so do not need further treatment. These high octane materials will consist of the branched chain or isoparaffins and certain high octane aromatic constituents such as benzene, toluene, etc.

The residual material comprises the low octane components and, where the original material was not within the gasoline range as will ordinarily be the case, also contains a large proportion boiling over and above the gasoline range. This fraction is then, after admixture with recycle gases and with recycle stock as hereinafter described, passed to a preheater where it is brought to the catalytic conversion temperature ranging from 900° to 1100° F., and preferably from 980° to 1050° F., and the heated stream is passed through a body of catalyst capable of effecting the desired catalytic dehydrogenation and gas reversion of the feed. The pressure in the conversion step will usually range from about 10 to about 1500 pounds per square inch gauge.

As catalyst, I usually use granular bauxite, especially hard Arkansas bauxite, since it is comparatively inexpensive and easily obtainable and as effective a catalyst as any I have found. Instead of bauxite, I may use chromium oxide, especially black unglowed chromium oxide, alumina, Activated Alumina, magnesia, catalysts of the type known as "silica-alumina" prepared by co-precipitating aluminum hydroxide and hydrous silica followed by calcining or by treating a partially dried hydrous silica gel with an aqueous solution of aluminum salt such as aluminum chloride or sulfate followed by washing and drying or prepared in any other known manner, adsorbent clay such as fuller's earth, acid-activated clay, charcoal, activated carbon, zirconium oxide, either alone or in admixture with aluminum oxide, bauxite impregnated with chromium oxide, brucite, gypsum, cadmium oxide, vanadium oxide, molybdenum oxide, tungsten oxide, zinc oxide, caliche of the limestone type, so-called "Houdry" catalyst, etc. Any of the synthetic catalysts such as alumina or zirconia may be rendered in porous form as by the process of Schulze 2,112,931. In the case of chromium oxide, it may be present in intimate admixture with a difficultly reducible oxide of aluminum, zirconium, titanium, silicon, thorium, boron or magnesium, as disclosed in Frey et al. Reissue 21,911. It will also be understood that the metallic compound catalysts may be supported on suitable inert or active carriers. Moreover the catalysts mentioned are not necessarily equivalents of one another.

The reactions taking place in the catalytic converter are not fully understood. However it is established that catalytic dehydrogenation and catalytic gas reversion (polyform) are major reactions occurring. The dehydrogenation effects conversion of paraffins to olefins. Some cyclization and aromatization may also accompany the dehydrogenation. All of these reactions increase the anti-knock rating of the hydrocarbon mixture being treated. The gas reversion is a process in

which occurs a reaction between normally liquid hydrocarbons and normally gaseous hydrocarbons, and especially of C₃ and C₄ paraffins and olefins derived from the catalytic effluent and that are recycled to the converter, to form materials of good anti-knock properties and in the gasoline boiling range. The catalytic gas reversion which occurs simultaneously with the straight catalytic dehydrogenation involves reversion of gaseous recycle with fresh feed, with unconverted recycle, and with polymerization products ordinarily formed in straight dehydrogenation. Due to the presence of substantial quantities of lighter material in the catalytic zone, increased yields are obtained. This gas reversion is catalyzed by the catalyst employed.

In addition to the foregoing reactions, catalytic reforming also takes place to a considerable extent and this further increases the content of high anti-knock compounds in the effluent. While the theory of reforming is not well understood, it is a well-known phenomenon and involves catalytic rearrangement of low anti-knock components of straight-run gasoline or naphtha to form substantially higher octane-number materials. Reforming is commonly considered to be a cracking process and may conceivably involve cracking of the feed to lower molecular weight components which then recombine under the influence of the heat, pressure and catalyst. Some conventional cracking and formation of lower molecular weight materials with incomplete recombination also take place so that normally gaseous hydrocarbons available for recycling are continuously formed anew.

Other reactions may also take place in the conversion zone, such as isomerization, polymerization and depolymerization, hydrogenation, catalytic alkylation, etc. Where sulfur is present, catalytic desulfurization also occurs.

By reason of the presence of recycle hydrogen in the catalytic step, "hydroforming" may also take place.

Preferably the conditions are so adjusted that the extent of conversion per pass through the catalytic converter is at least 20% and does not exceed 40% by weight based on the weight of fresh feed to the converter plus recycled normally liquid material.

If desired any normally gaseous material separated in the first fractionation where unstabilized feed was employed, and especially any C₃ and C₄ hydrocarbons such as propane and butane, may be introduced as gas reactant to the catalytic conversion step.

The effluent from the catalytic conversion zone is now fractionated into at least four fractions and preferably five or even six fractions.

The overhead or first fraction is normally gaseous and contains the non-condensable gases, namely C₂ hydrocarbons and lighter, i. e., ethane, any ethylene, methane, and hydrogen. It may or may not contain the C₃ and C₄ hydrocarbons, i. e., butane, any butenes, propane and any propylene. This overhead fraction, whether or not it contains the C₃ and C₄ components, may be further fractionated to separate essentially pure hydrogen, which is especially suitable for recycling. Where the C₃ and C₄ components are removed in this overhead fraction, the fractionation may also separate a fraction consisting of the C₃ and C₄ materials, these materials being particularly desirable as recycle stock, in addition to the hydrogen.

A second fraction of intermediate boiling point

and boiling in the motor fuel range is separated. This fraction constitutes the principal product of the process, it being of very good anti-knock quality, much higher than the feed or the gasoline portion of the feed. This fraction may be used as such as motor fuel, with or without blending, but preferably is blended with the high octane fraction initially separated as described above, since these two fractions have different characteristics and compositions and mutually beneficial blending properties so that the resulting motor fuel is more rounded or balanced, more complex and a better fuel. The product is a high octane "end point" motor fuel and has improved lead susceptibility.

A third fraction consists of material heavier than the motor fuel fraction just described and comprises mainly unconverted material, incompletely converted material and other materials lighter than tars and suitable for recycling. This third fraction is recycled in toto to the catalytic conversion step for further conversion along with fresh feed from the first fractionation step.

A fourth fraction comprising tars and the like heavy material undesirable for recycling is separated in the fractionating step under discussion and discarded from the system.

As pointed out above, if desired, the fractionation of the conversion effluent may be so conducted as to separate a fraction consisting of the C₃ and C₄ hydrocarbons which together with the pure hydrogen or a suitable portion thereof or with a portion of the entire C₂ and lighter fraction is passed to the catalytic step as the gas reactant for the gas reversion reaction therein. Usually an excess of this C₃ and C₄ fraction will be formed and it will be necessary to bleed off a portion thereof continuously from the system.

As will be obvious, the fractionation of the catalytic effluent may be conducted in one or a plurality of fractionators as necessary to give the desired separation. So-called "superfractionation" may be employed, if desired, for giving extreme closeness of cuts.

Referring now to the accompanying drawing, the raw distillate is fed via line 1 into the first fractionator 2 (which may be one or several columns) where a cut containing the high octane materials is separated and passes out via line 3 whence it may be removed as such from the system via line 4, though it is preferably blended with the main product of the process to form motor fuel as will appear below.

The low octane and heavy cut formed in fractionator 2 passes via line 5, which traverses heat exchanger 6 where it is heated by the hot catalytic converter effluent flowing in line 10, through heater 7 where it is brought to conversion temperature preferably from about 980° to about 1050° F., and thence via line 8 into one of catalyst towers 9 which are filled with an appropriate solid catalyst.

The effluent from catalyst towers 9 passes via line 10 through heat exchanger 6 and thence into fractionator 11 where it is fractionated into at least four cuts now to be described. A normally gaseous overhead (C₄ and lighter) fraction is taken off via line 12 whence it may be split, a portion passing via line 13 as recycle gases into the feed in line 5 and the balance passing via line 14 to fuel or any other use. A fraction in the motor fuel boiling range (from about 100° F. to about 400° F.), and which is the main product of my process, is taken off via line 15 and passed into admixture with the overhead

cut from fractionator 2 to form the preferred motor fuel product of my invention. A third fraction higher boiling than the fraction leaving via line 15 and comprising mainly unconverted or incompletely converted material is removed via line 16 and recycled to line 5 for further treatment in catalyst towers 9.

Occasionally it will be found desirable to effect a further separation in fractionator 11 (which may be either a single column or a series of columns as necessary to effect the desired fractionation) whereby the C₃ and C₄ are separated as a fraction by themselves, removed via line 17 and a portion passed via line 18 as the recycle gas into line 5, the excess leaving via line 19. This C₃ and C₄ fraction will be composed mainly of propane and butanes though propylene and butylenes may also be present in significant proportions. When this C₃ and C₄ fraction is used as the recycle gas for effecting the gas reversion in towers 9, no, or only a small proportion of the non-condensable gases (C₂ and lighter hydrocarbons and hydrogen) removed via line 12 will be recycled via line 13.

In any case, the excess gas leaving the system via line 14 may be passed to the flare, employed as fuel in the refinery, compressed and pumped back into the formation whence the distillate was recovered, or put to any other desired use.

It is desirable to always recycle a substantial amount of hydrogen in order to protect the catalyst against premature carbonization and deterioration, especially in the initial portion thereof. Thus, an especially desirable way to operate is to recycle C₃ and C₄ material via line 18 and to treat the C₂ and lighter non-condensable fraction taken off via line 12 (or a suitable portion of this fraction) in a unit 21 to segregate substantially pure hydrogen from the hydrocarbon content thereof, and recycle this essentially pure hydrogen in suitable amount to line 5, the hydrocarbon gases so separated leaving via line 22. However, hydrocarbons lighter than C₃, such as ethane, ethylene and methane, may also be recycled, in whole or only in part, if desired.

Provision is made in fractionator 11 to withdraw as a bottom product via line 20 any accumulation of unconverted products, tars and the like not desirable to recycle to the system.

The advantages of the described mode of operation are many. Among them are: An overall inferior "distillate" or straight-run naphtha is initially separated into its high and low octane fractions for separate treatment, thereby eliminating the necessity or disadvantage of cracking or processing branched chain high octane hydrocarbons by processing catalytically only the low octane fraction. The process results in a 94-98% yield of motor fuel hydrocarbons with a much improved octane number as compared with a previous yield of about 80% of motor fuel hydrocarbons having an inferior octane number when using simple fractionation of the distillate to recover only the gasoline range material. By recycling normally gaseous products derived from the fractionation of the catalytic effluent and also by recycling the heavier-than-motor fuel fraction similarly derived, under the conditions of temperature and pressure shown, catalytic reforming is obtained which may involve hydrogenation, catalytic reversion, catalytic cracking, catalytic dehydrogenation, catalytic alkylation and catalytic desulfurization or any possible hydrocarbon reactions to give better yields of a superior quality motor fuel. The process gives a

unitary, self-contained, economically operated method of converting "distillate" to a high grade motor fuel of good lead response, with a minimum of loss in the form of gases that must be vented and tars or similar unusable heavy material.

For example, the following operation illustrates the advantages of the invention. Of the total 50 octane raw condensate or "distillate" charged to a system as described above approximately 80% falls within the motor fuel range and has an octane number of around 58, which with 1 cc. of tetra ethyl lead gives 72 octane motor fuel. By treatment in accordance with the foregoing so as to obtain catalytic dehydrogenation and gas reversion of the low octane cut of this material, there is obtained an 85 to 90% yield of motor fuel which with 1 cc. of tetraethyl lead gives an 80 octane material.

The process is applicable to any gasoline stock of the type known as "straight-run," that is, to condensate or "distillate" of the type described at length above. Ordinarily the stock treated comprises a predominant proportion of material in the gasoline range, that is, from about 90° F. to about 400° F. or 425° F. The stock may cover a range of from an initial point ranging anywhere from about 90° F. to about 200° F. to an end point ranging anywhere from about 400° F. or 425° F. up to 650° F., and ordinarily is fairly well distributed over such a range. Ordinarily the stock treated by the process of my invention consists essentially of paraffins most of which are unbranched and therefore very low in octane rating. However, small amounts of unsaturates, i. e., olefins, cyclo-olefins, etc., small amounts of aromatics, cycloparaffins, naphthenes, etc., and substantial amounts of isoparaffins of high octane rating may be present.

As used herein, by the term "high octane" I mean having an octane number above 60 and usually at least 70 and by "low octane" I mean having an octane number not over 60, without using lead.

It will be understood that the foregoing disclosure is illustrative only and not limitative, and

that the invention is to be taken as limited only by the terms of the appended claim.

I claim:

- 5 A process which comprises subjecting a normally liquid condensate obtained from the hydrocarbon mixture occurring naturally in the gaseous phase in distillate wells under a pressure in excess of 1000 pounds per square inch to fractionation to separate a first fraction containing
- 10 the high octane components in the motor fuel boiling range and a second fraction containing the low octane and heavier components, passing said second fraction in the presence of recycled hydrogen and C₃ and C₄ hydrocarbons formed in this step in contact with a granular bauxite catalyst at a temperature within the range of approximately 900° to approximately 1100° F. and at a pressure within the range of approximately 10 to approximately 1500 pounds per square inch
- 15 gauge, fractionating the effluent from the last-named step to recover at least six fractions as follows: (1) a fraction consisting of essentially pure hydrogen, (2) a fraction containing C₂ and lighter hydrocarbons, (3) a fraction containing C₃ and C₄ hydrocarbons, (4) a normally liquid fraction containing the high octane components in the motor fuel boiling range, (5) a second liquid fraction containing the low octane components and components heavier than those in
- 20 the motor fuel boiling range, including unconverted and incompletely converted normally liquid components of the charge to said last-named step, and (6) a fraction containing tars and heavy material unsuitable for recycling, recycling at
- 25 least a portion of said hydrogen fraction (fraction 1) and at least a portion of said C₃ and C₄ fraction (fraction 3) to said catalytic conversion step, recycling said second liquid fraction (fraction 5) to said catalytic conversion step for additional conversion along with fresh material, and
- 30 blending said first-named high octane fraction with said second-named high octane fraction (fraction 4) to give a high octane motor fuel.
- 35
- 40
